PRESSURE PUMP

Clarence J. Coberly, Los Angeles, and Clyde F. Hanson, Maywood, Calif., assignors to RoKo Corporation, Reno, Nev., a corporation of Nevada

Application October 8, 1934, Serial No. 747,344

1 Claim. (Cl. 103—153)

This application is a continuation-in-part of our copending application, Serial No. 654,432, filed January 31, 1933, for High pressure pump, and relates to the same subject matter, it being a principal object of the invention to provide a high pressure pump in which an increased operating efficiency is attained.

The high pressure pumps known to us have low efficiency, and most of them need constant attention and frequent repair. We have produced a pump which will operate at pressures ranging from 4000 to 6000 pounds at high efficiencies and for long periods of time without need of attention. We have produced this pump as a result of inventive conception of means for overcoming the faults of the types of high pressure pumps now known to the pumping arts.

We believe that the principles of design now accepted include the idea that a nearly perfect seal should be maintained between the piston and the cylinder of a pump to prevent leakage of fluid around the piston and therefore loss of efficiency by waste. One of our conceptions is that by providing a definite clearance between the piston and the cylinder the reduction in friction between these two parts will result in a gain in efficiency which will more than offset the loss represented in the fluid which leaks past the piston in the cylinder. In conjunction with the foregoing, we have provided means for preventing the leakage fluid from entering the crankcase of the pumping mechanism and have accordingly avoided the possibility of dilution or contamination of the lubricant in the crankcase. These two elements employed in conjunction have materially contributed to the result of producing a high pressure pump having an efficiency often as high as 95% and being capable of continuous operation for a long period of time due to the minimized wear between its various parts. This is an important advance in high pressure pumps, that is, the pumping of fluids at pressures around or above 4000 pounds per square inch, especially when packed pumps similarly used have an efficiency ranging from 50% to 70%. The saving in pumping cost over the cost of pumping fluids under high pressures by old types of equipment is so large as to assume a position of material importance to the art. The foregoing are not merely laudatory statements but are believed to be statements of fact which must be presented if the invention is to be fully understood in all of its aspects.

An object of our present invention is to provide in a pump of the above character an im-

proved means whereby the capacity of the pump may be readily changed without material change in the speed of operation of the pistons, and in which pump a new and improved means for preventing passage of leakage fluid from the cylinders to the crankcase or the power mechanism of the pumping device is provided.

A further object of the invention is to provide a simple means for sealing around the cross-heads and for lubricating the cross-heads and other working parts of the power mechanism situated in the crankcase.

It is a further object of the invention to provide a pumping device having a simple and effective pressure relief valve and means for releasing pressure from the discharge passages of the pump.

A further object of the invention is to provide a high pressure pump comprising a cylinder with a piston operating therein, a crankcase having power means, and a chamber between the cylinder and the crankcase for receiving the leakage from the cylinder, together with means for pumping this leakage fluid from the chamber, so that no pressure can build up therein to force leakage fluid into the crankcase.

Further objects and advantages of the invention will be brought out in the following part of the specification.

Referring to the drawings:

Fig. 1 is a partly sectioned end elevation of a preferred form of our invention.

Fig. 2 is a vertical section to reduced scale taken as indicated by the line 2—2 of Fig. 1.

Fig. 3 is an elevational view of the rightward end of Fig. 2 with the power unit of the device removed.

Fig. 4 is a horizontally sectioned view taken on the line 4—4 of Fig. 2.

Fig. 5 is a fragmentary section taken as indicated by the line 5—5 of Fig. 1.

Fig. 6 is an enlarged fragmentary section through the pressure relief valve of the device, taken on the plane represented by the line 6—6 of Fig. 1.

Fig. 7 is a slightly enlarged sectional view on a plane represented by the line 7—7 of Fig. 2.

Fig. 8 is an enlarged cross-sectional view taken as indicated by the line 8—8 of Fig. 2.

Fig. 9 is a fragmentary section on a plane represented by the line 9—9 of Fig. 2, showing the oil jets for lubricating the cross-heads.

Fig. 10 is an enlarged sectional view through the damping valve of the device.

The preferred form of our pump, as disclosed

in the drawings, includes a crankcase 11 which is spaced from a cylinder block 12 by a hollow member 13, the parts 11, 12, and 13 being secured together by means of bolts 14. The block 12 has three vertical bores 18 which are diametrically reduced at their upper ends 20 and communicate with three lateral openings 21. In the main or large portion of each bore 18 below the diametrically restricted upper end thereof is a replaceable liner 23 which slides readily into the bore 18 and has a flange 24 near its lower end adapted to slide into a counterbore 25 formed at the lower end of the bore 18 and to be therein held against a packing ring 26 by means of a sleeve 27 which is threaded into the lower portion of the counterbore 25. The piston 28 is made from an accurately ground metal bar, and the lower end thereof extends into a chamber 30 formed in the hollow body 13, so as to make engagement with the upper end of a stem 31 forming the upper end of a cross-head 54. The connection of the piston 28 with the cross-head stem 31 is accomplished by use of a threaded bar or stud 33 having a flange 34 substantially in the center thereof to serve as a spacer between the ends of the members 28 and 31.

The lower wall 35 of the member 13 has openings 36 therein through which the cross-head stem 31 reciprocates, and disposed in each of the openings 36 is a packing means 37 adapted to wipe the shaft or stem 31. On the upper portion of each stem 31 a dripper plate 38 is secured. This dripper plate is preferably secured between the ends of the associated piston 28 and cross-head stems 31 and comprises a plate with downwardly turned edge portions, such plate being of such diameter that the leakage fluid which passes down around the piston 28 through its surrounding cylinder insert 23 will be deflected laterally outwardly when it reaches a dripper plate 38 and will drip from the edges thereof into drainage channels 40 formed in the bottom wall 35 of the hollow body 13. The mechanism within the crankcase 11 comprises bearings and gears 45 which are accurately made and fitted and which will operate with a minimum resistance and for a long period of time if kept properly lubricated and free from abrasive substances. By use of the dripper plates within the chamber 30 and 50 drainage channels 40, together with means for removing from the drainage channels the leakage fluid which has dripped thereinto from the dripper plates 38, we are able to completely prevent the entrance of leakage fluid into the crankcase and thereby avoid all possibility of thinning of the lubricant carried in the crankcase and of contamination of the crankcase lubricant by such abrasive substances as may be carried by the leakage fluid. Under these conditions it 55 is found that the mechanism within the crankcase gives efficient and long service.

The crankcase 11 has end walls 44 and 45 equipped with annular bearing-receiving walls 46 and 47 in which bearings for a crank-shaft 48 are supported. On the leftward end of the crank-shaft 48 a heavy ball bearing 50 is employed. On the rightward end of the crank-shaft 48 a roller type bearing 51 is used. On the crank pins 52 of the shaft 48, connecting rods 53 are 60 mounted, each of which extends upwardly to a cross-head 54 operating in a cross-head guide 55 substantially in vertical alignment with a bore 36 of the body 13. The upper ends of the connecting rods 53 engage tubular wrist pins 56 which are set transversely in the cross-heads 54

and are secured by screws 57 which project upwardly through the lower end walls of the wrist pins and are held against displacement by securing wires 58 tied through holes in the upper ends of the screws 57. The stems 31 of the cross-heads 54 may be integrally formed therewith, as shown.

As shown in Figs. 1 and 5, a horizontal passage 65 is formed in the block 12 below the planes of the lateral passages 21 and adjacent the upper ends of the bores 18 to provide a fluid inlet 10 passage for the pump into which fluid to be pumped may be conducted through piping 66 secured to the rightward end of the block 12 by a flange 67. Connecting each of the lateral passages 21 with the passage 65 is an opening 15 68 which is outwardly flared at its upper portion to provide a seat 70 for a replaceable valve seat 71 forming part of a valve unit 72 which further includes a closure member in the form of a steel ball 73 and means for resiliently holding the ball 20 73 in engagement with the seat 71, such means comprising a spring 74 and a tubular member 75 which is slidably received in a vertical, downwardly facing recess 76 of a threaded member 77, there being four downwardly extending legs 25 78 on the lower end of the tubular member 75, the lower ends of which legs are curved to fit the upper face of the ball 73 so that when the spring 74 holds the member 75 downwardly, the engagement of the legs 78 with the ball 73 will 30 resist lateral movement of the ball 73 when it is raised from the seat 71. The members 77 screw into threaded openings 80 which are vertically aligned with the valve seat 71 and accordingly provide removable vertical guides for the ball-retaining means represented by the members 75.

A high pressure discharge passage 81 for the pump is drilled longitudinally in the block 12 above the plane of the lateral passages 21 and rearwardly with respect to the inlet passage 65, 40 or to the left of the block 12 as shown in Fig. 1. As further shown in Figs. 1 and 2, vertical openings 68a connect the leftward ends of the passages 21 with the passage 81, and above the openings 68a threaded openings 80a are extended 45 from the passage 81 to the upper end of the block 12. In the openings 68a and 80a valve units 72 are operatively secured so as to prevent reverse flow of fluid under pressure from the passage 81 into the lateral passages 21. One end of the passage 81 is connected through a flange fitting 83 with piping 84 for carrying the fluid under pressure to a desired point of utility. The end of the passage 81 opposite the fitting 83 is connected through a pipe 85 with a pressure gauge 55 86 which may be conveniently secured to the front face of the block 12. An intermediate portion of the passage 81 connects through an opening 87 with a pressure relief valve 88 secured to the rearward face of the block 12. 60

As shown in Figs. 1 and 6, the relief valve 88 includes a cylindrical body 91 having laterally projecting flanges 92 formed thereon through which bolts 90 may be passed to secure the device 88 to the rear face of the block 12. The cylindrical body 91 has a downwardly facing recess 93 which is threaded at 94 to receive a downwardly extending cylindrical shell 95 having a lower end wall 96 with an opening 97 therein through which a shaft 98 extends, the lower 70 extremity 99 thereof being squared to receive a wrench and being protected by a downwardly extending cylindrical apron wall 101 which prevents turning of the shaft 98 except by use of the proper wrench therefor. The shaft 98 has 75

5 a flange 102 thereon which rests against the upper face of the wall 96, and the upper portion 103 of the shaft is threaded to receive a spring 104 having a flange 105 equipped with projections 106 engaging vertical guide grooves 107 in the interior wall of the shell 95. Supported on the flange 105 is a spring 108, the upper end of which engages a circular plate 110 having a central opening 111 adapted to receive the downwardly projecting cylindrical stem 112 of a conical valve member 113. The conical valve member 113 engages a tubular seat member 114 which threads into an opening 115 extending upwardly from the recess 93. The upper end 15 of the opening 115 connects with the opening 81, Fig. 1, through a downwardly sloping passage 116. From the upper part of the recess 93, to one side of the opening 115, a passage 117 extends through a vertical wall 118 into communication with the upper face of a flange 120 formed at the upper end of the wall 118, to which flange piping 120a may be attached for carrying off the fluid which is forced from the passage 81 of the pump past the pressure-retained valve 20 element 113 into the recess 93 and the interior of the shell 95. A gasket 121 may be placed between the flange 102 of the member 98 and the wall 96 to prevent leakage of fluid through the opening 97 in the lower end of the shell 95. The 25 adjustment of the pressure relief valve mechanism may be readily accomplished by rotating the shaft 98 so as to screw the spring compressor upwardly or downwardly, thereby suitably changing the pressure with which the valve element 30 35 113 engages the seat 114.

Means are provided for releasing the fluid pressure from the discharge passage 81 of the pump and the discharge piping 84 and to conduct the fluid or liquid which is removed in so 40 doing into the return piping 120a which is shown leading to the reservoir 43 for the pumped fluid. An important use of our invention is at present in conjunction with fluid operated deep well pumps wherein oil is pumped under a high pressure to a fluid operated pump situated in an oil well. When it is desired to disconnect the pressure piping which leads down through the well to the pump therein, the high fluid pressure must be relieved. This, of course, may be done by 45 cracking one of the joints so that the oil may be forced therefrom, but such practice is wasteful and generally results in spilling oil on the derrick floor. We provide means in conjunction with the pressure relief valve for releasing fluid from 50 the high pressure passage of the pump and from the pressure fluid delivery piping into the piping which leads to the oil reservoir, thereby avoiding the above noted unsatisfactory conditions. To 55 accomplish this, a hole 41 is drilled upwardly 60 from the space 93 within the body 91 to meet a threaded opening 42, the inner end of which connects with an opening 44 leading into the sloping passage 116. The rightward end of the screw 43 is conically pointed and is normally held, as 65 shown in Fig. 6, in a position to close the opening 44. When the screw 43 is rotated so that it will move outwardly or leftwardly, the passage 44 will connect with the passage 41, and fluid under 70 pressure will drain through the sloping passage 116 from the passage 81 and also from the pressure piping 84 which is connected thereto. Packing means 45a is provided around the screw 43, and this is compressed so as to produce a tight 75 seal by means of a threaded sleeve 42a having a recess 43a therein for access to the squared end

44a of the screw 43 by use of a suitably formed socket wrench. The squared end 44a of the screw 43 is submerged in the recess 43a so that it cannot be engaged except by use of a wrench especially provided therefor. 5

The invention provides simple means for automatically removing the leakage oil from the channel 40 in the member 13, such means consisting of a gear pump 123 formed in conjunction with a cover plate 124 secured to the annular 10 wall 46 which holds the bearing 50. As shown in Figs. 2 and 7, the plate 124 is provided with a leftwardly or outwardly extending boss 125 having a pair of overlapped circular recesses 126 and 127 therein, the recess 126 being aligned with 15 the axis of rotation of the crank-shaft 48. A pump gear 128 of spur type operates in the recess 126 and has a shaft portion 130 extending therefrom through an opening 131 in the cover plate 124 into driving engagement with an opening 132 in the crank-shaft 48. In the recess 127 is a gear 134 which meshes with the gear 128 and rotates on an axle 135, the outer end of which is seated in a pocket 136 in a circular plate 137 which is secured to the boss 125 in position to 20 cover the recesses 126 and 127. As shown in Figs. 1 and 2, the plate 137 has a laterally extending and outwardly projecting metal body 138 formed thereon in which openings 140 and 141 are bored 25 in radial direction, and the inner ends of these 30 openings 140 and 141 are connected with the inner face of the plate 137 through holes 142 and 143 which are respectively positioned so as to communicate with the spaces 144 and 145, Fig. 7, 35 which are respectively the intake and discharge 35 passages of the gear pump when the gear 128 is rotated in the direction of the arrow 146 of Fig. 7.

By use of fittings 147, a pipe 148 connects the channel 40 with the opening 140, Fig. 1, and a pipe 150 connects the opening 141 with the recess or chamber 93 of the pressure relief valve 88; accordingly, whenever the device is in operation, the leakage from the pistons and cylinders accumulating in the channels 40 drains through the pipe 148 into the opening 140 and is conducted through the opening 142 into the space 144 of the gear pump 123 and is delivered therefrom under pressure through the openings 143 and 141 and the pipe 150 into the space 93 in the pressure relief valve, from which space 93 50 it is conducted through the outlet passage 117 to piping which may be connected to the flange 120 so as to be from there carried into a fluid supply tank or other means of disposal. The 55 piston and cylinder leakage is accordingly kept from entering the crankcase 11. In the opening 141 a check valve may be employed in the form of a ball 152 held in closure position by a spring 153.

The fittings 147 are of simple construction 60 and are of such character that the pipes 148 and 150 may be readily removed whenever it is desired to dismantle the parts of the pump, and each of such fittings comprises a bar or stem 154 having a threaded inner end 155 so as to be 65 screwed into an opening. Extending outwardly from the inner end of the member 154 is an opening 156 which connects through radial openings 157 with an external circular chamber 158 formed on the member 154. Around the projecting cylindrical portion of the member 154, a bored block 160 is placed, such block being clamped between gaskets 161 and 162 by means of a cap nut 163. One side of the block 160 has a projection 164 through which an opening 165. 70 75

extends into communication with the peripheral channel 158 of the bar 154. To this projection 164 an interconnecting pipe, such as the pipe 148, may be welded so that the block 160 of the connecting means then becomes the end part of the pipe 148. By removing the nut 163, removal of the block 160 from the projecting portion of the bar 154 is permitted, and reassembly of these parts may be readily accomplished by placing the block on the projecting bar or stem 154 between the gaskets 161 and 162 and then replacing the nut 163.

In Fig. 3 the pipe 85 is shown connected to the high pressure passage 81 of the pump and to the pressure gauge 86 by use of connecting devices 147a. Each of the connecting devices 147a is constructed so as to provide a flow restricting or damper valve for damping the pulsations in the high pressure fluid which passes through the piping 85 to the gauge 86. As shown in Fig. 10, this damping valve is simply formed by providing the fitting 147a with a threaded bar or stem 154a similar in external form to the member 154 of Fig. 1. This member 154a is provided with a small diameter axial opening 156a which connects with an axial opening 156b which is threaded to receive a needle pin 149 adapted to act as a closure or flow restricting means for the outer end of the passage 156a. From the inner end of the passage 156b diagonal ports 157a are extended outwardly so as to connect with an annular space 158a which is formed within a block 160a and communicates with the piping 85 extending to the pressure gauge 86. The outer portion of the valve pin 149 is provided with packing means 159, and the outer extremity of the pin 149 may have a screw-driver slot 159a by which it may be adjusted.

The fitting 147a is similar to the fittings 147 previously described but differs from them by having the nut 163 formed integral with the outer end of the bar member 154 instead of separate therefrom.

In Fig. 2 the gear case 15 and the cover 16 therefor enclose a space in which reduction gears are operatively held. Keyed to the rightwardly projecting end 170 of the crank-shaft 48 is a gear 171 adapted to be driven by a pinion 172 formed on a shaft 173 which is carried in a ball bearing 174 mounted in the outer face of the wall 45, and a bearing 175 mounted in a recess 176 in the inner face of the gear case cover member 16. On the rightward portion of the shaft 173 a gear 177 is mounted, adapted to be driven by a small pinion 178 secured to the end of a motor shaft 180 which projects into the gear case cover 16 through an opening 181 which is counterbored at its outer end to provide an annular bearing recess 182 to receive a ball bearing 183 for the motor shaft 180. The gear case cover 16 has a disc-shaped wall 184 providing a circular lip 185 for engaging the cylindrical frame or case 186 of a motor 187, the wall 184 forming the leftward end bell or end wall of the motor 187 when the frame 186 thereof is secured against the wall 184 by bolts 188 which pass through openings 190 of Fig. 3. Feet 189 for the rightward end of the pumping device may be conveniently formed on the gear case cover 16, and feet 191 for the leftward end of the pumping device may be cast on the crank-case 11.

The opening 181 in the gear case cover 16 is of such size that the pinion 178 will readily pass therethrough, thereby making it possible

to remove the motor 187, its armature, its shaft 180, and the pinion 178. The power of the motor 187 may be varied by changing the length of the field and armature; accordingly, where the pump is intended for light duty, a relatively short motor, as indicated by dotted lines 192, may be mounted thereon. The changing of the power unit of the pumping device may be accomplished without disturbing the gears in the gear case 15 other than by the removal and replacement of the pinion 178.

The means for lubricating the mechanism within the crankcase are shown in Figs. 2, 8, and 9. The bearings 50 and 51 and the crank pins 52 are lubricated by the fact that they operate partly submerged in the body of lubricating oil which is placed in the crankcase 11. The gear 171 also passes through this body of oil and carries quantities of the oil to the pinion 172. Between the cover plate 124 and the leftward end of the crankcase 11 and the leftward face of the bearing 50 an oil pump 200 is held. This oil pump comprises a circular plate 201 through which the shaft member 130 extends. Near the rightward end of this shaft member 130 is a gear 202 which operates in a recess 203 formed in the leftward face of the plate 201. A second gear 204 operates in the recess 203 in engagement with the gear 202 and cooperates therewith to form a gear pump. The lower portion of the plate 201 has an opening 205 therein through which oil from the crankcase may pass to the lower end of a vertical slot or passage 206 formed in the lower inner face of the cover plate 124 to carry the lubricating oil upwardly to the inlet zone 207 of the gear pump formed by the gears 202 and 204. Extending upwardly in the inner face of the cover plate 124 from the discharge or outlet zone 208, shown in Fig. 8, is a discharge passage 209 which connects at its upper end to a hole 211 drilled inwardly in the crankcase 11, as shown in Fig. 2, to meet the lower end of a vertical hole 212, the upper end of which connects with a groove 213 formed in the upper face of the crankcase 11. When the pumping device is in operation, the gear 202 rotates in anticlockwise direction, as shown in Fig. 8, and lubricating oil is pumped from the crankcase under pressure to the oil passage consisting of the holes 211 and 212 and the channel 213.

As shown in Fig. 9, small openings 215 are drilled through the inner bead or wall portion 216 defining the inner wall of the oil passage 213 in the upper part of the crankcase 11, for discharge of streams of oil to lubricate the cross-head stems 31 and the cross-head bearings 56. As indicated by an arrow 217 in Fig. 9, a small stream of oil is discharged against one side of each of the cross-head stems 31 so as to lubricate the same. This oil collects in the depressions 218 formed in the upper faces of the cross-heads 54, and a portion of the same passes through diagonal openings in the upper parts of the cross-heads, as shown at 219, to the oil opening 220 at the upper end of each connecting rod 53. As shown in Fig. 2, an opening 221 is drilled downwardly from the rightward portion of the oil channel 213 to meet an opening 222 which extends laterally in the gear case 15 which connects with an opening 223 in the upper wall of the gear case cover 16. From the leftward end of the opening 222 a small hole 224 is drilled downwardly to discharge oil to the inner face of the bearing 174 which supports the leftward end of the shaft 173, and an opening 225 is placed

so as to discharge oil downwardly along the rightward face of the bearing 174. In the wall of the gear case 16 a small opening 226 is drilled in a position to discharge oil against the gear 171 so that the teeth of this gear and of the pinion 178 will be lubricated. An opening 227 is drilled so as to discharge oil from the passage 223 in such a manner that a stream of oil will be delivered to the bearing 185 which supports the rightward end of the shaft 173.

The pumping device hereinbefore described will operate for long periods of time without attention, for the reason that the parts thereof are adapted to operate with a minimum of friction and wear. The friction between the pistons 28 and the cylinder members 23 is minimized by making these parts so that there will be an actual clearance therebetween instead of employing a seal such as packing which will bear with pressure and consequently friction against the faces of the pistons 28. A slight leakage of oil past the pistons is intended, and to prevent this leakage fluid from contaminating the oil in the crankcase or from otherwise producing wear of the mechanical operating parts, means are provided for positively preventing the entry of leakage fluid into the crankcase and also for preventing contact of the leakage fluid with the cross-head stems 31. As previously described herein, this result is produced by use of dripper plates 38 and by means which will positively remove the leakage fluid from the channels 40 in the lower portion of the hollow body 13 so that the leakage fluid will not accumulate in the hollow body 13 so as to engage the cross-head stems. Accordingly, the cross-head stems 31 cannot operate to carry contaminating leakage fluid downwardly through the openings 36 through which they pass.

Friction between the pistons 28 and the cylinder members 23 is minimized by making the members 23 so that they may be aligned with and by the pistons 28. A further feature of importance to the invention is that the capacity of the pump may be varied within reasonable limits without the necessity of making expensive parts to replace those parts shown. The pistons 28 are of extremely simple form and are attached to the upper ends of the cross-head stems 31 in a

simple manner. Should it be desired to reduce the capacity of the pumping device without a change in the speed of operation, or vice versa, the pistons 28 may be replaced by pistons of suitable diameter, and the cylinder members 23 5 may be replaced by others of a size to cooperate with the new pistons 28. Also, should a change in the pressure of the pumped fluid be desired, the motor 186 may be readily replaced by one of desired capacity, as previously explained. 10

Although we have herein shown and described our invention in simple and practical form, it is recognized that certain parts or elements thereof are representative of other parts, elements, or mechanisms which may be used in substantially 15 the same manner to accomplish substantially the same results; therefore, it is to be understood that the invention is not to be limited to the details disclosed herein but is to be accorded the 20 full scope of the following claim.

We claim as our invention:

A high pressure pump of the character described, including: a power mechanism having a cross-head reciprocating vertically and a stem 25 projecting upwardly from said cross-head; a cylinder block having a bore facing downwardly toward said stem; a wall defining a space between said bore and said power mechanism having an opening through which said stem passes; 30 a piston extending from the upper end of said stem into said bore; a cylindrical liner in said bore to receive said piston, said liner having an external diameter less than the diameter of said bore so as to be laterally adjustable to align 35 with said piston, and said piston being of such smaller diameter than the bore of said liner as to cause a definite flow of fluid through said liner into said space whereby to produce a free movement of said piston in said liner; means for holding said liner in said bore; a dripper plate on 40 said stem above said opening for preventing passage of said fluid from said bore onto the portion of said stem which passes through said opening; and pump means automatically operating in consequence of the operation of said 45 power mechanism to remove said fluid from said space.

CLARENCE J. COBERLY.
